(57) **CLAIM**

(22) Filed: **Aug. 1, 2007**

The ornamental design for a medical loupe with head set, as shown and described.

(30) **Foreign Application Priority Data**

Feb. 7, 2007 (EM) 000666359

DESCRIPTION

(51) **LOC (9) Cl.** 24-01

FIG. 1 is a perspective front view of a medical loupe with head set of my new design;

(52) **U.S. Cl.** D24/231

FIG. 2 is a top plan view of said medical loupe with head set of FIG. 1;

(58) **Field of Classification Search** D24/137,

FIG. 3 is a bottom plan view of said medical loupe with head set of FIG. 1;

D24/150, 160, 186, 231; D26/24, 27, 39,
D26/51, 113, 120; D29/103; D16/311, 133,
D16/135–136, 309; 362/105–106, 573, 804;
600/249, 111, 109; 359/409

FIG. 4 is a right side elevational view of said medical loupe with head set of FIG. 1;

See application file for complete search history.

FIG. 5 is a left side elevational view of said medical loupe with head set of FIG. 1;

(56) **References Cited**

FIG. 6 is a front elevational view of said medical loupe with head set of FIG. 1; and,

U.S. PATENT DOCUMENTS

FIG. 7 is a rear elevational view of said medical loupe with head set of FIG. 1.
